UNITED STATES PATENT OFFICE.

RALPH C. SEYMOUR, OF LARCHMONT, NEW YORK, ASSIGNOR TO GOSS PRINTING PRESS COMPANY, OF CHICAGO, ILLINOIS, A CORPORATION OF ILLINOIS.

SHEET-HANDLING MACHINE.

1,024,460.

Specification of Letters Patent.

Patented Apr. 23, 1912.

Application filed June 15, 1910. Serial No. 567,103.

To all whom it may concern:

Be it known that I, RALPH C. SEYMOUR, a citizen of the United States, and a resident of Larchmont, in the county of West-
5 chester and State of New York, have invented new and useful Improvements in Sheet-Handling Machines, of which the following is a specification.

The invention relates to sheet handling
10 machines and more particularly to machines for cutting printed sheets from a printed web and delivering same, although in certain of its features the invention is applicable to other kinds of printing machines.

15 Objects of the invention are to provide a novel mechanism for easily and rapidly delivering two printed sheets received in succession from the press into separate piles; to provide such a mechanism adapted to operate upon a web; to provide in connection with such a mechanism novel means for transferring the sheets from one conveying means to another; to provide a novel sheet delivery which is very rapid, and is also
20 simple in construction and reliable in operation; to provide such a mechanism adapted to operate upon a web fed thereto and also adapted to deliver the sheets flat.

These and other objects of invention will
25 in part more fully appear hereinafter and will in part be obvious to those skilled in the art.

The invention consists in the novel parts, constructions, arrangements, combinations, and improvements herein shown and described.

The accompanying drawings, referred to herein and forming a part hereof, illustrate one embodiment of the invention, the same
40 serving in connection with the description herein to explain the principles of the invention.

45 Of the drawings:—Figure 1 is a side elevation, with the front frame removed, of a machine constructed in accordance with the principles of the invention; Fig. 2 is a sectional plan on the line A—B of Fig. 1 looking in the direction of the arrows; Fig. 3 is a fragmentary view of the sheet cylinders
50 showing the cylinder taking a second sheet and associating it with a sheet already on the cylinder, the chain conveyer gripper being shown in advance; Fig. 4 shows the chain conveyer grippers closing on the
55 sheets as they are released by the cylinder

grippers; and Fig. 5 shows the sheets being carried away by the chain conveyer grippers.

Referring to the accompanying drawings, illustrating by way of example one embodiment of the invention, a web 1 is shown running into the machine over a roller 2. It will be understood that a plurality of webs could be run in in the same manner. Said web is directed downwardly through a 60 throat formed by a series of guide fingers 3 and an opposing series of guide fingers 5. The guide fingers 3 are mounted upon a rod 4, said rod being carried on the machine frame, and the fingers 5 are carried upon a 65 similar rod 6. Suitable sheet cutting means are provided and the form thereof shown herein comprises opposed rotating knives 10 and 11 located on opposite sides of the web as it travels between the roller 2 and the 70 throat formed by the sets of fingers 3 and 5. The knife 10 is shown mounted on disks 12 carried by a shaft 13. The knife 11 is shown mounted on a series of disks 14 carried by the shaft 15. 75

80 Means are provided for collecting the sheets and delivering them at each side of the machine. Sheet associating means are provided at either side of the path of travel of the sheets in operative relation with the 85 sheets to take them as they are fed along said path and severed from the web by the cutters. A cylinder 20 is shown carried by the shaft 21, rotatably mounted on the machine frame. A set of grippers 22 on the 90 cylinder 20 take the lower end of the sheet first before it is severed by the cutters 10 and 11. A set of tapes 25 is shown running over rollers 27 and 28 to hold the sheets upon the cylinder. The grippers 22 collect 95 or associate a plurality of sheets before releasing them for delivery. In the present instance, the grippers take the end of one sheet and carry it around the cylinder, then on the next revolution of the particular cylinder 20, these grippers take the end of another sheet and then pass both sheets on as herein, as more fully explained later
herein.

100 For the purpose of taking the sheets from the cylinder 20 and conveying them away and delivering them, grippers traveling about said cylinder for a portion of its circumference and away to a place of delivery are provided. The relative speed of these 110

grippers to those on the cylinder while passing about the cylinder is such that the sheets will be transferred from the cylinder grippers to said traveling grippers. According to one feature of the invention, the traveling grippers are in advance of the cylinder grippers and travel at a slower speed, the grippers thus meeting and transferring the sheet from the cylinder grippers to the traveling grippers. In the embodied form sprocket chains 30 and 31 carry a set of grippers 32. Means for opening and closing these grippers at the proper time are provided, and for this purpose one jaw of said grippers 32 is fixed to the hollow bar 33, which is fixed to the chains 30 and 31. Rotatably mounted within said hollow bar 33 is a rod 34 to which the other gripper jaw is fixed. As the bar 34 is caused to rotate or reciprocate within the hollow bar 33 each pair of gripper jaws opens or closes. When said bar is not acted on, the grippers may be held in the closed position by spring pressure. For the purpose of actuating the rod 34, it is provided at each end with crank arms 35 and 36, provided respectively with rollers 37 and 38. The sprocket chains 30 and 31 pass over sprocket wheels 40 and 41 shown with their hubs formed as sleeves 42 and 43 rotating on the shaft 21, between the cylinder 20 and the side frames of the machine. The sprocket wheels 40 and 41 are of such size and so positioned and the series of grippers 32 are so located upon the sprocket chains, that as they travel together the hollow bar 33 with its grippers meet a depressed or cut out portion 50 in the surface of the cylinder 20. Thereby the bar 33 travels around with the cylinder 20 lying in the said recess 50 and with the bite or center of the gripper jaws substantially in the surface of the cylinder.

The chains 30 and 31, on the side of the cylinder 20 away from the sheet path lead away from said cylinder past suitable delivery devices, and in the present instance, pass over sprocket wheels 55 and 56 mounted upon a rod or shaft 57. The chains 30 and 31 are constructed and arranged to travel somewhat more slowly than the surface of the cylinder 26, and in the present embodiment said chains are somewhat less in length than twice the circumference of the cylinder 20, thus, notwithstanding that the chains travel a little slower than the surface speed of the cylinder, the grippers will always pass over the cylinders in the same relative position. The sprocket wheels are driven by gears 110 and 111, fixed to each sprocket wheel shaft 57 and 103, respectively, and suitably driven to give the requisite difference in speed between the chain grippers and cylinder grippers. The depression 50 is located adjacent to the set of grippers 22, and the parts are so timed that the grippers

32 will enter the depression 50 slightly in advance of the cylinder grippers 22. The grippers 22 are closed upon the sheets π holding them to the cylinder 20. The grippers 32 are held open, the rollers 37 and 38 running on the cams 60 and 61 (see Fig. 2). Owing to the slower rate of travel of the sprocket chains 30 and 31, as the cylinder rotates the open grippers 32 travel in the depression 50 relatively to the grippers 22 and the sheets π , until one jaw of each pair of the grippers 32 is on each side of the sheet held by the grippers 22, as shown in Fig. 4 of the drawings. Any suitable means may be employed for opening the grippers 22 to release the sheets as the grippers 32 close upon them. The illustrated form of such means comprises a crank arm 221 fixed to the shaft 222 of the grippers 22. An arm 331 is shown fixed on the bar 33 having a contact piece 332 which engages the cam roll 223 on arm 221 to rock the grippers 22 open (see Fig. 4): the gripper closing when said arm 331 moves away, after the grippers 32 have taken the sheets. The bar 33 is now close upon the grippers 32 but this occurs at or very near the place where the sprocket chains are leaving the cylinder, and the gripper 22 rides off along its circular path (see Fig. 5) having been opened to release the sheets π which have just been gripped by the grippers 32, the sheets π thus traveling away with the grippers 32 being carried off the cylinder as the grippers 32 travel away with their chains. A suitable delivery table 65 may be provided upon which the sheets are stacked and if desired a finger 66 may be employed to bring them down. The jaws 32 are opened by the cams 67 and 68 engaging the rollers 37 and 38. From the foregoing it will be seen that each alternate time that the grippers 22 re-

From the foregoing it will be seen that each alternate time that the grippers 22 rotate, the grippers 32 are in operative relation with them, as shown in Figs. 3, 4 and 5, and that in the intervening rotation the grippers 32 are not in operative relation with them. When the grippers 22 reach the sheet taking point they close down upon the end of the sheet which is then severed by the cutters 10 and 11, the sheet being carried around upon the cylinder 20. When the grippers 22 again come around to the sheet taking point they close down on the end of a second sheet, the tapes 25 holding the first sheet upon the cylinder. On this rotation the grippers 32 are in proper relation for taking the sheets from the grippers 22 in the manner previously described, and the sheets are carried away by the grippers 32, one sheet being taken off the cylinder, and the other running between the cylinders directly from the cutters and the web. So far as many features of the invention are concerned, however, the parts could be so proportioned and arranged as to associate 110

ciate a greater number of sheets, or to take only one sheet at a time directly from the web and deliver it. Suitable means are provided for opening and closing the grippers 22 to take the ends of the sheet at each revolution, and to release the sheets to the grippers 32 at every second revolution, but said gripper actuating means are not shown herein, it being old and well known in the art to provide mechanisms to actuate sheet grippers at every revolution of the cylinder, or at every second revolution. Upon the opposite side of the path of travel of the sheets is shown a cylinder 80 provided with grippers 81 for taking the sheets, which may be similar to the corresponding parts previously described. The cylinder 80 is mounted on the shaft 82 in the machine frame. Mounted in operative relation with said cylinder 80 are the sprocket chains 85 and 86 working over the sprocket wheels 87 and 88 which may have their hubs 89 and 90 loosely sleeved upon the shaft 82 and hereinbefore described with relation to the corresponding parts. A set of grippers 91 are carried on the hollow rod 92 within which rotates the shaft 93. The rod 93 is provided with cranks 94 and 95 having rollers 96 and 97. One jaw of each pair of the grippers 91 is fixed to the hollow bar 92, and the other to the rod 93, reciprocating therein to open and close the grippers as desired. The sprocket chains 85 and 86 pass around the cylinder 80 so that the grippers 91 will come within the recess 100. The sprocket chains then run upwardly and around the sprocket wheels 101 and 102 upon the shaft or rod 103. Cams 104 and 105 may be provided to coöperate with the rolls 96 and 97 to open the grippers 91 to receive the sheet, and cams 106 and 107 may coöperate therewith to cause the grippers to drop the sheets upon the delivery table 108. Detailed description of these parts, and of their manner of operation is unnecessary, as they may in all essential points be identical with or similar to the parts on the other side of the machine.

In addition to the explanation of the manner of operation of the mechanism which has already been included in connection with the description of the structure, it will be noted that the grippers 22 of the cylinder 20 and the grippers 81 of the cylinder 80 are a half rotation apart, and that they thus take the sheets alternately as they are run down the pathway and are cut off by the rotary cutters. It will also be noted that the set of grippers 32 on the chains 30 and 31 and the set of grippers 91 on the chains 85 and 86 follow each other and come into operative relation with their respective gripper cylinders on successive rotations thereof.

Each of the cylinders 20 and 80 collect

two sheets, one of said sheets being taken by one of said cylinders, and the next sheet by the other cylinder. Considering the sheets as run down and cut off *seriatim* as one, two, three and four, sheets one and two may be duplicates of each other and sheets three and four may be duplicates of each other. Cylinder 20 will take sheet one and carry it around and cylinder 80 will take sheet two and carry it around. Cylinder 20 will then take the end of sheet three and transfer sheets one and three associated to the grippers 32 which carry them off and deliver them. Cylinder 80 will then take the end of sheet four, and transfer sheets two and four to the grippers 91 which will carry them off and deliver them. It will be understood that the number of sheets collected and the timing of parts, are illustrative and explanatory of the invention and not restrictive thereof.

The invention, in its broader aspects, is not limited to the particular construction shown, nor to any particular constructions by which it has been or may be carried into effect, as many changes may be made in the construction without departing from the main principles of the invention and without sacrificing its chief advantages.

What I do claim as my invention and desire to secure by Letters Patent, is:

1. A sheet handling machine including in combination means for supplying a web, means for cutting the web into sheets, two cylinders adjacent to each other, means for directing the sheets between said cylinders, grippers on each of said cylinders for taking the alternate fed sheets, one on one cylinder and the next on the other, each of said grippers collecting two sheets, sprocket wheels at each end of each cylinder, and concentric with said cylinders, sprocket chains engaging said sprocket wheels and extending away from the opposite cylinder, said sprocket chains being slightly less in length than twice the circumference of said cylinder, a plurality of sprocket wheels located away from said cylinders, one of said sprocket chains passing over each of said last mentioned sprocket wheels, a support extending across between the two sprocket chains coöoperating with the same cylinder, grippers carried upon said support, and means for opening and closing said grippers.

2. A sheet handling machine including in combination web supplying means, means for cutting the web into sheets, two cylinders adjacent to each other, means for directing the sheets between said cylinders, sheet collecting means on said cylinders for taking alternate sheets as they are cut from the web, sprocket wheels at each end of each cylinder, sprocket chains passing over said sprocket wheels and traveling at a less speed than the surface speed of said cylinders,

- and sheet taking means carried by the pair of chains associated with each cylinder, said sheet taking means passing over the surface of said cylinder and receiving the sheets from said sheet collecting means upon said cylinders.
3. A sheet handling machine including in combination web supplying means, means for cutting the web into sheets, two cylinders adjacent to each other, means for directing the sheets between said cylinders, sheet collecting means on said cylinders for taking alternate sheets as they are cut from the web, sprocket wheels at each end of each cylinder, sprocket chains passing over said sprocket wheels and traveling at a different speed than the surface speed of said cylinders, and sheet taking means carried by the pair of chains associated with each cylinder, said sheet taking means passing over the surface of said cylinder and receiving the sheets from said sheet collecting means upon said cylinders.
4. A sheet handling machine including in combination web supplying means, means for cutting the web into sheets, two cylinders adjacent to each other, sheet grippers upon each cylinder for taking and collecting the sheets, grippers mounted on a traveling carrier and passing over one of said cylinders to receive the collected sheets from the cylinder grippers, and other grippers mounted upon a traveling carrier and passing over the other cylinder to receive the collected sheets from the cylinder grippers.
5. A sheet handling machine including in combination web supplying means, means for cutting the web into sheets, two cylinders adjacent to each other, sheet grippers upon each cylinder for taking and collecting the sheets, grippers mounted on a traveling carrier and passing over one of said cylinders to receive the collected sheets from the cylinder grippers, and other grippers mounted upon a traveling carrier and passing over the other cylinder to receive the collected sheets from the cylinder grippers, one of said traveling grippers delivering to one place of delivery and the other of said traveling grippers delivering to another place of delivery.
6. A sheet handling machine including in combination a cylinder, collecting grippers thereon for collecting a plurality of sheets, and a gripper carrier traveling over the face of said cylinder at a slower speed than the collecting grippers to receive the sheets therefrom and to convey them away from the cylinder to a place of delivery.
7. A sheet handling machine including in combination a cylinder, grippers thereon, and grippers traveling in a partly circular and a partly non-circular path, and passing about said cylinder during the circular portion of their travel to receive the sheets from the cylinder grippers.
8. A sheet handling machine including in combination a cylinder, grippers thereon, sprocket chains at either side, a gripper bar extending across between said chains, and means for traveling said chains at a different speed from the surface speed of the cylinder to transfer a sheet from the cylinder grippers to the chain grippers.
9. A sheet handling machine including in combination a cylinder having a longitudinal recess therein, grippers on said cylinder near one end of said recess, and a set of grippers adapted to travel in said recess and at a slower speed than the cylinder whereby a sheet is transferred from one set of grippers to the other.
10. A sheet handling machine including in combination a set of grippers traveling in a circular path, and a set of grippers traveling in a path partly circular and partly non-circular, the circular part being substantially concentric with a portion of the path of the other grippers, said grippers traveling at different speeds and passing each other at a point where their paths diverge and means for causing a sheet to be conveyed from one gripper to the other at said point.
11. A sheet handling machine including in combination means for supplying sheets along a path, means traveling past a point in said path to collect sheets one at a time from said point in said path, and means traveling with said means past said point in said path after a plurality of passings and collectings by said collecting means to receive the collected sheets from said collecting means.
12. A sheet handling machine including in combination means for supplying sheets along a path, means traveling past a point in said path to collect sheets one at a time from said point in said path, and means traveling with said means but at a different speed past said point in said path after a plurality of passings and collectings by said collecting means to receive the collected sheets from said collecting means.
13. A sheet handling machine including in combination a plurality of sets of grippers traveling in substantially concentric paths at different speeds and means for supplying sheets to one of said sets of grippers, the other set of grippers delivering said sheets.
14. A sheet handling machine including in combination two sets of grippers traveling in endless paths; means for traveling said grippers at different speeds, whereby one set of grippers passes the other, the forward grippers traveling more slowly, means for opening the forward grippers prior to

their being overtaken by the rear grippers and means for opening the rear grippers and closing the forward grippers as they pass.

5 15. A sheet handling machine including in combination two sets of grippers traveling along substantially the same path, means for traveling said grippers at different speeds, whereby one set of grippers passes 10 the other, the forward grippers traveling more slowly, means for opening the forward grippers prior to their being overtaken by the rear grippers, and means for opening the rear grippers and closing the forward 15 grippers as they pass.

16. A sheet handling machine including in combination a plurality of sets of grippers traveling in substantially concentric paths at different speeds, and means for 20 suitably opening and closing said grippers as they pass, whereby a sheet is transferred from one of said grippers to the other.

17. A sheet handling machine including in combination means for supplying sheets

along a path, rotary means at the side of 25 said path for taking a sheet therefrom, and means traveling along a rotary path substantially concentric with that of said rotary means but at a slower speed, whereby the sheet may be delivered from said rotary 30 means to said traveling means.

18. A sheet handling machine including in combination a cylinder, grippers thereon, grippers traveling in a partly circular and a partly non-circular path, and passing about 35 said cylinder during the circular portion of their travel to receive the sheets from the cylinder grippers and delivering the sheets during the non-circular portion of their travel.

In testimony whereof, I have signed my name to this specification, in the presence of two subscribing witnesses.

RALPH C. SEYMOUR.
